UNITED STATES PATENT OFFICE.

CARL G. GULBRAND, OF LOS ANGELES, CALIFORNIA.

RAIL-HOLDING TIE.

Application filed April 18, 1927. Serial No. 184,669.

My invention relates to railway ties, and more particularly to a tie which is formed or cast with rail holding means therein adapted to be manipulated for the purpose 5 of clamping a rail to the tie or releasing it at will, with means for securing said holding means against accidental release.

One of the salient objects of my invention is to provide a railway tie of cast material, preferably of concrete, with cavities or chambers formed therein on the under side thereof, with openings up through the top thereof, and in which are placed during the forming thereof holding members adapted 10 to be manipulated from an inoperative position to an operative position whereby a rail placed thereon can be clamped to the tie or released by the manipulation of said holding members.

Another object of my invention is to provide in such a tie means for resiliently supporting the rail thereon, and upon which yielding means said rail is held by said holding members.

In order to fully explain my invention, I have illustrated one practical embodiment thereof on the accompanying sheet of drawings, which I will now describe.

Figure 1 is a perspective view showing a 30 section of a rail tie embodying my invention, with a section of a rail thereupon;

Figure 2 is a fragmentary view, partly in section, of a railway tie embodying my invention;

Figure 3 is a sectional view through a tie and rail and showing my improved holding member in place therein;

Figure 4 is a perspective view of the end 40 of a railway tie embodying my invention, in section; and

Figure 5 is a plan view of a fragmentary section of tie and rail and holding member, with parts broken away.

Referring now more in detail to the drawings, it will be understood that my improved tie is to be cast of any suitable casting material, such as concrete, though not limited to concrete. In the drawings the tie body is designated 1 in all views, and cavities 45 formed therein to lighten the structure are designated 1'.

There is also shown a holding member cavity under each rail and this cavity is designated 1^a and is of special form, as indicated 55 in Fig. 3 in particular, and in which a holding member 2 is placed, being inserted

up through said opening 1^a from the underside, said holding member in its illustrating form being of general U-form with a middle stem portion giving it something the form 60 of the letter W, with the two upper ends of the side arms or members bent to angles, 2^a, 2^a, and in opposite directions, the middle member, designated 2^b terminating under the base of the rail, designated 4, while the 65 angle or toe portions, 2^a, 2^a, are adapted to be turned to overlie and wedge down upon the base flange, 4^a, at the opposite sides of said rail 4, as clearly illustrated, Fig. 3.

In casting or forming the tie 1, and the 70 cavity 1^a, there are two body portions 1^e, 1^e, which rest between the arms of the holding member, as indicated in Fig. 3, and upon these portions I have shown resilient or yielding members 3, 3, to underlie the base 75 of the rail and give a cushion effect between the rail and tie. These may be rubber balls, as shown in Figs. 2 and 3, or coiled springs, as 6, may be used, and to this end the top of the tie body is formed with a transverse 80 channel 1^e to receive the base or flange of the tie, with the diagonally spaced top cavities up through which said holding members 2^a, 2^a, project and seat, substantially in the manner indicated. Said holding member as 85 here shown is adapted to turn about its center and to this end the cavities up through which the side arms project are elongated, as will be clear from Fig. 5, and are adapted to receive wedge members, designated 5, to 90 hold the toe portions 2^a, 2^a, in place upon the rail flanges, as indicated. Said diagonally spaced top cavities are designated 7, 7, and the ball or spring cavities are designated 8, 8, while the opening up through 95 which the middle member of the holding member projects is designated 9, Fig. 4.

The operation of the device may be briefly described as follows: The specially formed or cast ties are put into place upon the right-of-way with the holding members inserted up through the cavities provided for them, as illustrated in Fig. 2. When the rail is placed thereupon, as shown in Figs. 1 and 3, said holding members are turned to position 100 their bent portions 2^a upon the flanges of the rail, at opposite sides thereof, as shown clearly in Fig. 3, and then the wedge members 5 are put into place to hold the holding members in their operative positions, as seen 105 in Fig. 5. The resilient members 3, 3, are placed in the proper cavities in the formed

tie, under the base of the rail, to form a cushion between rail and tie.

I do not limit my invention to the details used to illustrate one embodiment of my invention, realizing that many changes can be made therein without departing from the spirit thereof, except as I may be limited by the hereto appended claims.

I claim:

10 1. A cast railway tie having cavities formed therein from the underside thereof with openings up through the top surface of said tie, holding members inserted up through said openings and having angle portions adapted to be turned simultaneously to overlie and clamp a rail flange to said tie.

20 2. A railway tie of the character shown and described having rail receiving channels formed transversely across the top of said tie and having openings up through said tie from the underside, forked holding members inserted up through said tie from the underside and having angle parts adapted to be turned to overlie and clamp the flange of a rail onto said tie.

30 3. A railway tie formed of cast material and having cavities formed therein from the underside up through said body, resilient members set in the top of said tie to receive the base of a rail, a forked holding member for each rail inserted up through said tie from the underside and having angle tie

portions adapted to be turned simultaneously to overlie and clamp said rail flange upon said tie body.

35 4. A railway tie of cast material having rail receiving channels in its top and cavity seats in connection therewith, resilient means in said seats, a holding member inserted up through said tie from the underside for each rail, said holding member having two arms provided with angle portions and diagonally positioned relative to each other, said holding member being adapted to be turned about its axis to move said angle portions into holding engagement over the flange of a rail upon said tie.

40 5. A cast railway tie having rail receiving channels in its top, diagonally opposed openings up through said tie body from the underside, a holding member having two side arms and one center piece extended up through said tie body, said side arms having angle portions at their ends and adapted to be turned to overlie the opposite sides of the flange of a rail placed upon said tie, and wedge means for holding said side arms and said angle portions in clamping position upon said rail flange, substantially as described.

50 Signed at Los Angeles, Los Angeles County, California, this 12th day of April, 1927.

CARL G. GULBRAND.
